UNITED STATES PATENT OFFICE.

ALFRED FRANCIS REILLY, OF NORTH ATTLEBORO, MASSACHUSETTS.

DESIGN FOR A VANITY CASE.

Application filed November 22, 1921. Serial No. 517,115. Term of patent 3½ years.

To all whom it may concern:

Be it known that I, ALFRED F. REILLY, a citizen of the United States, and a resident of North Attleboro, in the county of Bristol and State of Massachusetts, have invented a new, original, and ornamental Design for a Vanity Case, of which the following is a specification, reference being had to the accompanying drawing, forming part thereof.

I claim:

The ornamental design for a vanity case, as shown.

ALFRED FRANCIS REILLY.
